UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 22,063, dated December 20, 1892.

Application filed November 22, 1892. Serial No. 452,880. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons and other Similar Articles, of which the following is a specification, reference being had to the accompanying drawing, forming a part thereof.

The figure is an upper or front face view of a spoon handle embodying my design.

The leading feature of my design is a special arrangement of the leaves, blossoms and buds of the tree rose applied to the handle of the spoon as follows. Upon the shank of the handle is laid a twig with three leaves *a*.

Just above it are two blooms or blossoms *b b* of the tree rose nearly opened, and just above these is a large and full blown rose *c*. 20 Two buds *d d* and two leaves *e e*, one on each side of the buds, are disposed at the extreme end of the handle. The outer edges of the leaves, blossoms, and buds impart their irregular outline to the margin of the handle. 25

What I claim is,

The design for the handles of spoons and other similar articles as herein shown and described.

AUSTIN F. JACKSON.
